UNITED STATES PATENT OFFICE.

PAUL J. BALTTEIM, OF JERSEY CITY, NEW JERSEY, ASSIGNOR TO
J. SCHWARTZ & CO., OF NEW YORK, N. Y.

DESIGN FOR A PERFUMERY-CASE.

SPECIFICATION forming part of Design No. 16,923, dated October 5, 1886.

Application filed July 28, 1886. Serial No. 209,453. Term of patent 7 years.

To all whom it may concern:

Be it known that I, PAUL J. BALTTEIM, of Jersey City, in the county of Hudson and State of New Jersey, have invented a new and original Design for a Perfumery-Case, of which the following is a specification.

This design relates to an ornamental perfumery case.

The nature of my design is fully represented to in the accompanying photograph, to which reference is made.

The special features of my design consist in a perfumery-case, a middle part, doors and inclined top, and an upper oblong part on the said top, and a pyramidal part on the oblong part.

A represents in the photograph the middle part or case of my perfumery-case. b is the enlarged base; B, doors in the middle part, 20 and d the top or roof.

E represents an oblong part on the roof, and F a pyramidal top part. A thermometer is shown on the pyramidal top part, and a clock-dial in the oblong part E.

Having thus described my design, I claim as new and desire to secure by Letters Patent—

The design for a perfumery-case, consisting of a lower part or base, a middle part with two doors, an inclined top or roof, an intermediate oblong part on the top or roof, a clock-dial in the oblong part, a pyramidal part on the oblong part, and a thermometer in the pyramidal part, as shown and described.

In testimony that I claim the foregoing as my invention I have signed my name in presence of two subscribing witnesses.

PAUL J. BALTTEIM.
